UNITED STATES PATENT OFFICE.

DANIEL N. PRIME, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SKIVING AND FOLDING MACHINE.

1,281,654.

Specification of Letters Patent. Patented Oct. 15, 1918.

Application filed March 7, 1916. Serial No. 82,753.

To all whom it may concern:

Be it known that I, DANIEL N. PRIME, a citizen of the United States, residing at Lynn, in the county of Essex and State of Massachusetts, have invented certain Improvements in Skiving and Folding Machines, of which the following description, in connection with the accompanying drawings, is a specification, like reference characters on the drawings indicating like parts in the several figures.

This invention relates to machines for finishing the edges of sheet material and is herein illustrated in connection with a machine for skiving, folding and pressing the margin of a part of the upper of a shoe and for introducing into the fold prior to the pressing operation an adhesive filament.

Hitherto it has been customary to apply cement in liquid form to the skived margin of a piece of upper leather before presenting said piece to the folding instrumentalities of a folding machine. Attempts to embody cement applying apparatus in such a machine have thus far not met with success for various reasons, among others for the reason that liquid cement which will properly stick down the flap of the fold requires an interval for drying between the time of its application to the material and the time of the folding and pressing operations in order to render it properly tacky.

According to one feature of the invention an adhesive filament is introduced into the fold, after which coöoperating pressing members relatively movable toward and from each other grip and press the fold and the inclosed filament. By making use in this manner of an adhesive filament which is normally tacky but not wet, the operation of cementing the margin in the manner hitherto practised may be dispensed with.

Another feature of the invention relates to the provision in a machine of this type of means for skiving the margin of the material prior to folding the margin and introducing into the fold the adhesive filament. With this combination of mechanisms the skiving operation, as commonly carried out on a separate machine, is no longer necessary.

These and other features of the invention, including certain details of construction and

combinations of parts will be described as embodied in an illustrative machine and 55 pointed out in the appended claims.

Referring to the accompanying drawings,

Figure 1 is an elevation of a machine in which the present invention is embodied; 60

Fig. 2 is a plan view, the overhanging arm having been broken away;

Fig. 3 is a section on the line 3-3 of Fig. 1;

Fig. 4 is a section on the line 4-4 of 65 Fig. 1;

Fig. 5 is a section on the line 5-5 of Fig. 1;

Fig. 6 is a detail, partly in section, of the grippers which press the fold and feed the 70 stock;

Fig. 7 is a perspective from above of the skiving, tape applying and fold forming and pressing elements;

Fig. 8 is a perspective from beneath of 75 the tape applying, folding and pressing elements.

The illustrative machine is adapted to skive the margin of a piece of flexible material, to fold the skived margin over a piece 80 of adhesive tape, and to press the fold thus formed, the purpose of the tape being primarily to hold the flap of the fold firmly attached to the body of the material thereby avoiding the necessity which has hitherto 85 existed of applying cement to the skived margin prior to the folding operation.

Referring first to Fig. 1, the skiving mechanism is similar to that shown in United States patent to Alexander No. 1,079,462 90 and comprises a hollow base 1 having a flat top through which protrudes a cylindrical skiving knife 7. A feed roll 9 advances the stock to the knife and a presser-foot 11 holds the stock down on the roll, an edge gage, not 95 shown, being provided to guide the edge of the stock. Inasmuch as the details of the skiving mechanism form no part of the present invention and any suitable skiving mechanism may be used, no further description 100 of said mechanism will be given other than to point out that the cylindrical knife is fast to a shaft 13 and that the feed roll is fast to a shaft 15 which is connected by a worm and gear with a shaft 17 said latter shaft 105 being connected with the shaft 13 by a belt

19. It will be understood, that the operator faces the machine as viewed in Fig. 1 and presents the stock from left to right with its margin beneath the presser foot 11 and that said margin is skived progressively as the stock is advanced by the feed roll to the knife.

From the skiving mechanism the skived margin of the stock is engaged by a folder 10 21 by which it is folded about a strip 23 of adhesive tape, said tape running from a reel 25 down around an idle roll 27 and up between two small feed rolls 29. The grippers 31, 32 first swing over the fold, then 15 press it, then draw it diagonally upward toward the small feed rolls 29, then release the fold and return to the position shown in the drawings. The tape is coated on both sides with adhesive material with the result 20 that the flap of the fold is, by the action of the grippers or pressers 31, 32, stuck firmly to the body of the stock.

With this brief outline of the mode of 25 operation of the machine the details of the mechanism for operating the feed rolls 29 and the pressers 31, 32 will now be described.

Referring more particularly to Figs. 1, 4 and 6, an upright shaft 33, driven from the shaft 17 by bevel gears 35, 37, carries fast 30 to it a bevel gear 39 which meshes with a bevel gear 41 on a horizontal shaft 43 to which are fast two gears 45, 47 and a barrel cam 49. The gear 47 meshes with a gear 51 of the same size said gear being integral 35 with a sleeve 53 upon the farther end of which is formed a cam 55. The gear 45 through a gear 57 drives a gear 59 which is fast to a shaft 61 upon which the sleeve 53 is revolvable, said shaft having fast to it a 40 cam 63 which is the companion to the cam 55. These two cams, the function of which is to open and close the grippers or pressers 31, 32 as well as to move them bodily in the direction of the line of feed, are set one 45 hundred and eighty degrees apart and, by the gearing which has been described above, are rotated at the same speed but in opposite directions.

The two grippers or pressers 31, 32 have 50 stems 131, 132 which are pivoted at 65 in a carriage 67 held between two flat faced stationary guides 69, the carriage being thus free to slide as well as to move angularly in any path not prevented by the flat faced 55 guides. Inasmuch as the connections between the stems 131 and 132 and their respective cams 55 and 63 are identical, only that between the stem 132 and the cam 63 will be described. The upper end of this 60 latter stem is in the form of a two-part yoke which is connected with a cam follower 69 by trunnions 71, the purpose of which will presently appear. With the construction thus far described it will be clear 65 that rotation of the cams 55 and 63 opens

and closes the grippers 31, 32 and moves them bodily up and down in an inclined path determined by the flat faced guides 69.

In order to swing the grippers bodily toward and from the tape 23 at the proper time, a roll 73, mounted upon a pin 75 which is integral with the carriage 67, runs in the track 149 of the barrel cam 49. The cams 55, 63 and 49 are so timed that a four-motion feed is imparted to the grippers 31, 32, said 75 grippers first swinging from the position shown toward the operator until they are respectively below and above the adjacent portion of the tape and the folded material, then closing upon the fold, then moving 80 bodily diagonally upward, then opening and moving away from the operator and finally returning to the position shown, this cycle of movements being repeated continuously as long as power is applied to the shaft 13. 85 Inasmuch as the stem 132 of the gripper 32 extends diagonally across the stem 131 of the gripper 31, the hole in the stem 132 through which the pivot 65 passes is elongated as shown in Fig. 6. 90

The feed rolls 29 are formed by the ends of two small shafts (see Fig. 3) the upper one of which carries a bevel gear 77 which meshes with a bevel gear 79 on an inclined shaft 81, to the upper end of which is fast a 95 bevel gear 83 (see Fig. 2) meshing with a bevel gear 85 fast to that shaft 61. The upper one of the small shafts, the ends of which form the rolls 29 (see Fig. 3), also carries a gear 87 which meshes with a gear 100 89 on the lower shaft, the bearing of the lower shaft being pivoted at 91 and urged upwardly by a spring 93 the tension of which may be controlled by a screw 95.

Referring now more particularly to Figs. 7 and 8, the operation of the machine as a whole will be explained. As the stock is fed from left to right, the margin of the stock is skived by the knife 7, the chip or skiving passing under the cutting edge of 110 said knife and the skived stock above it. The skived margin rides up on the sticky tape 23 and is engaged by the folder 21 which bends a portion of the skived margin down over the edge of the tape and up beneath the same thereby forming the fold in the stock 100. The grippers 31, 32 then swing toward the tape under the action of the roll 73 and barrel cam 49, and during this swinging movement the lower gripper 115 31 tends to wipe the folded over margin into proper position if it is not already in such position. The grippers then close on the fold and press the inner surfaces thereof tightly against the tape. The grippers are 120 then moved diagonally upward toward the rolls 29, after which they open, move away from the tape and return to their initial position ready to repeat the cycle of movements. The folded margin passes between 130

the rolls 29, the body of the stock being supported by the operator until the selected margin thereof has been entirely folded and pressed. In use the run of tape from the 5 idle roll 27 for a considerable distance back toward the reel 25 is covered by a guard, but this has been omitted from the drawing to promote clearness.

The moving parts of the machine are so 10 timed that the roll 9 and the grippers 31, 32 operate to feed the work at the same rate, the movements of the grippers being such that their successive bites overlap so that they act upon all portions of the folded 15 edge. The rolls 29 tend to feed the work faster than do the grippers 31, 32 and the roll 9. The tension of the spring 93, however, is so adjusted that the gripping action of these rolls is not sufficient to feed the thin 20 tape when only the tape is between them but merely to maintain the tape taut. As soon as the folded edge is fed between them by the grippers, the gripping action of the rolls 29 is increased to such an extent that they are 25 capable of taking up any slack in the work but not of feeding the work except as permitted by the roll 9 and grippers 31, 32. The purpose of this mode of operation of the 30 rolls 29 is to permit the machine to be run continuously while no leather piece is being operated upon.

The tape illustrated comprises a strip of fabric coated on both sides with a sticky but comparatively dry adhesive. It should 35 be understood, however, that the particular nature of the adhesive element is immaterial and that by the term "adhesive filament" is included any adhesive element which may be introduced progressively into 40 the fold. And although particular skiving, folding and pressing mechanisms have been illustrated it should be understood that the invention is not limited in the scope of its application to the particular mechanisms or 45 types of mechanisms shown and described.

Having thus described my invention, I claim as new and desire to secure by Letters Patent of the United States:

1. A machine of the class described, having, in combination, fold-forming means, 50 means for introducing into the fold a comparatively dry but tacky filament, coöperating pressing members relatively movable toward and from each other, and means for intermittently causing relative movement between the members to grip and press the fold and the inclosed filament.

2. A machine of the class described, having, in combination, means for progressively 55 folding the margin of a piece of flexible material, means for introducing an adhesive filament into the fold, means for pressing the fold and the inclosed filament, and means for bodily moving the pressing means to 60 feed the material.

3. A machine of the class described, having, in combination, means for progressively folding the margin of a piece of flexible material, means for introducing an adhesive filament into the fold, means for pressing 70 the fold, and the inclosed filament, and means for bodily moving the pressing means to feed the material and the filament.

4. A machine of the class described, having, in combination, fold forming means, 75 means for introducing into the fold an adhesive filament, coöperating pressing members relatively movable toward and from each other, and means for intermittently causing relative movement between the members to grip and press the fold and the inclosed filament.

5. A machine of the class described, having, in combination, fold forming means, 80 means for introducing into the fold an adhesive filament, coöperating pressing members, and means for swinging one member toward the other to press the adhesive element firmly against both sides of the interior 85 of the fold.

6. A machine of the class described, having, in combination, means for forming a fold in the margin of a piece of flexible material, means for introducing into the fold an adhesive filament, coöperating fold-pressing 90 members, a pivot on which one member is mounted and about which it may move into and out of contact with the work, and means for moving said last-named member about its pivot to press the fold and the inclosed 95 filament.

7. A machine of the class described, having, in combination, means for skiving the edge of a piece of flexible material, means for forming a fold in the margin having the 100 skived edge, and means for introducing into the fold an adhesive filament.

8. A machine of the class described, having, in combination, means for skiving the edge of a piece of flexible material, means for forming a fold in the margin having the 105 skived edge, means for introducing into the fold an adhesive filament, and means for pressing the fold.

9. A machine of the class described, having, in combination, means for skiving the edge of a piece of flexible material, means for forming a fold in the margin having the skived edge, means for introducing into the fold an adhesive filament, and reciprocating 115 means for gripping the fold to press it.

10. A machine of the class described, having, in combination, a stationary folder past which the material is fed, a member located in proximity to said folder and located to 120 direct into the fold an adhesive filament, and oscillatory means for pressing the filament inside the fold.

11. A machine of the class described, having, in combination, a stationary folder past 125

which the material is fed, a roll located in proximity to said folder and located to direct into the fold an adhesive filament, and oscillatory means for pressing the filament inside 5 the fold.

12. A machine of the class described, having, in combination, means for forming a fold in the margin of a piece of stock, and means for pressing the fold, said last-named 10 means comprising pivoted gripping members, and means for swinging said members toward each other.

13. A machine for operating upon parts

of boots and shoes, having, in combination, means for feeding a piece of material into 15 position to have its margin operated upon, means for progressively forming a fold in said margin, means for introducing into the fold a dry adhesive filament, cooperating pressing members, and means for swinging 20 one member toward the other to press the adhesive filament firmly against both sides of the interior of the fold.

In testimony whereof I have signed my name to this specification.

DANIEL N. PRIME.
